UNITED STATES PATENT OFFICE.

JOHN C. NICE, OF OCKLEY, INDIANA.

CHURN.

SPECIFICATION forming part of Letters Patent No. 453,360, dated June 2, 1891.

Application filed March 11, 1891. Serial No. 384,608. (No model.)

To all whom it may concern:

Be it known that I, JOHN C. NICE, a citizen of the United States, residing at Ockley, in the county of Carroll and State of Indiana, 5 have invented certain new and useful Improvements in Churns; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain new and 15 useful improvements in churns; and it has for its object to improve upon the construction and to render more efficient in operation this class of appliances.

The invention consists in the peculiar construction and in the novel combination, arrangement, and adaptation of parts, all as more fully hereinafter described, shown in the accompanying drawings, and then specifically defined in the appended claim.

25 The invention is clearly illustrated in the accompanying drawings, which, with the letters of reference marked thereon, form a part of this specification, like letters of reference indicating like parts throughout the several 30 views, and in which drawings—

Figure 1 is a perspective view of a churn embodying my improvements, with parts broken away in order to better illustrate the construction and arrangement of the parts. 35 Fig. 2 is a vertical longitudinal section of the same. Fig. 3 is a vertical transverse section, and Fig. 4 is a bottom plan view, of the cover.

Reference now being had to the details of the drawings by letter, A represents the body 40 of the churn, which is preferably rectangular in form, and is supported by the strips B, which are secured to the side faces of the body A, and unite at their upper ends at a point above the upper face of the churn. The crank-shaft C is journaled within suitable bearings provided for the purpose within the upper 45 ends of the strips B, and one of the ends of the said shaft is provided with an operating-crank C'.

50 The dasher D is rectangular in form and is secured at its center to the lower end of the dasher-shaft D', the upper end of the said

shaft being sleeved upon the crank C² of the crank-shaft C.

The inner faces of the side walls of the 55 churn-body are each provided at their longitudinal centers with vertical strips E, and the dasher D is provided with transverse strips D², which are secured to the upper face of the dasher, the ends of the strips extending 60 beyond the outer edges of the dasher upon each side of the strips E, the said strips thus serving as a guide for the dasher in its vertical movements, as will be readily understood. It will be noticed that the edges of the strips 65 D² are rounded upon the side adjacent to the guide-strips E, thus permitting the dasher to be given a slight rocking motion, as will presently be explained.

The cover G is made in two sections, as 70 shown, and is provided with a longitudinal slot G' for the passage of the dasher-stem D'.

H is a strip or block, of either wood or metal, which is loosely sleeved upon the dasher-stem. This block is adapted to enter a space 75 provided for its reception upon the inner face of the cover, and serve as a means for locking the cover in place. This locking mechanism will be best understood upon reference to Fig. 4 of the drawings, in which I have shown a 80 bottom plan view of the cover. The strips J are secured to the under face of the cover along the longitudinal edges thereof, and attached to the said strips are blocks J', which extend for a short distance beyond the inner 85 edges of the strips J, and when the cover is placed upon the churn the block H upon the churn-dasher stem is raised and one of the ends of the block is placed within the space intervening between the cover and the blocks 90 J'. The section G² of the cover is provided upon its under face with strips J², the ends of which extend for a short distance beyond the end of the section G², and these projecting ends engage the under face of the opposite section of the cover, thus serving to lock the same in place, as will be readily understood.

The operation of the churn is simple and readily understood. By turning the crank a 100 vertical reciprocating motion will be imparted to the dasher, and at the same time a slight rocking motion will be imparted thereto. The block H serves to effectually hold the cover

in position, and as the block is allowed to move freely beneath the blocks J' a free movement of the dasher-stem is permitted. The rods or strips L, which are pivoted at 5 their upper ends upon pivots or bolts extending from the inner faces of the strips B, serve, when turned downward so as to cause their lower ends to bear upon the cover, as an additional means for holding the cover in place. 10 These rods or strips may, however, be omitted, if desired.

Having thus described my invention, what I claim to be new, and desire to secure by Letters Patent, is—

15 The combination, with a churn having a vertically-reciprocating dasher, of the two-

part cover to the churn, having longitudinal opening G', the strips J, secured along the under face of the cover at the sides thereof, the transverse blocks J', secured to said strips 20 and extended beyond the inner edges thereof, the block H upon the dasher-stem, and the longitudinal strips J² on the under face of one section of the cover, all substantially as shown and described. 25

In testimony whereof I affix my signature in presence of witnesses.

JOHN C. NICE.
